SEWING MACHINE

George Sauer, Chicago, Ill., assignor to Union
Special Machine Company, Chicago, Ill., a cor-
poration of Illinois

Application August 25, 1942, Serial No. 455,977

13 Claims. (Cl. 112—256)

1

This invention relates to an improved construction for sewing machines having a rotary loop-taker or hook of the vertical axis type and more particularly to a construction by which adequate, but accurately regulated, lubrication of the hook raceway and other portions of the hook assembly of such machines is insured.

An object of the invention has been to provide a simple, compact and readily accessible device for accurately regulating the supply of lubricant to the raceway of a vertical axis hook from a reservoir disposed below the plane of said raceway. A feature, in this connection, is the provision of a single member which serves both to induce or assist in the pumping of the lubricant, and to regulate the flow of the lubricant so pumped. The arrangement is such that the capacity of the pumping means is normally in excess of the requirements of the raceway but the flow actually created by the pumping means is restricted, through manual adjustment of a part of such means, so as to cause delivery of just the right amount of lubricant. The adjustment of said part is readily effected from the exterior of the machine, without the removal of any elements, so that compensation may easily be made for variations in flow due to wear of the parts, the use of lubricants of different viscosities, or due to substantial changes in the speed of operation of the machine. Adequate lubrication of the raceway may, accordingly, be provided at all times without danger of soiling the work or the thread and without wastage of oil.

In the preferred form of the invention the lubricant supply and the means for pumping and regulating its flow are formed as a unit in the frame or saddle which carries the hook. The latter is provided with a hollow shaft through which the lubricant is fed by the pumping action of means within the bore of the shaft. This means, preferably in the form of a spirally grooved core pin, is supported for axial adjustment within said bore and through such adjustment serves to restrict more or less, the flow of oil through the bore, induced by rotation of the hook shaft.

Another feature of the invention is the provision of constantly effective means for lubricating certain cam or eccentric devices associated with the hook unit and taking part in the operation of the same. At the same time, contamination of the lubricant by dirt or by particles worn from the cooperating surfaces of the driving gears is avoided so that the delivery of only clean oil to the hook raceway is insured.

Other objects, features and advantages of the

2

invention will appear from a detailed description of an illustrative form of the same which will now be given in conjunction with the accompanying drawings, in which:

Fig. I is a top plan view of a portion of the base of a sewing machine embodying the present invention, certain cover plates being removed.

Fig. II is a bottom plan view of said portion of the base, parts of certain oil reservoirs being broken away for purposes of better illustration of their interiors.

Fig. III is an enlarged, vertical sectional view along the line III—III of Fig. I.

Fig. IV is a perspective view of a cover element embodied in the improved machine.

Fig. V is a perspective view of a gasket associated with the cover element.

Fig. VI is a detail view in axial section through a bushing embodied in the machine.

Fig. VII is a transverse, vertical sectional view along the line VII—VII of Fig. I.

Fig. VIII is a horizontal sectional view on a reduced scale taken along the line VIII—VIII of Fig. III, and

Fig. IX is a detail view partly in elevation and partly in section taken along the line IX—IX of Fig. VIII.

Referring now to the drawings, the invention has been shown in connection with a machine of the general type more fully disclosed in the application of Oscar Quist, Ser. No. 326,828 filed March 30, 1940, which has matured into Patent No. 2,329,484, Sept. 14, 1943 and in applicant's pending application Ser. No. 436,554 filed March 28, 1942. Reference may be had to said prior pending applications for further details as to the construction and operation of parts of the machine forming the setting for the novel devices herein more fully disclosed.

The illustrative machine comprises a vertical standard (not shown) rising from one end of a base portion 9. A laterally extending arm (also not shown) which overhangs the base portion is provided at the upper end of said standard.

In this overhanging arm there are suitable devices for supporting and operating a needle bar which carries at its lower end a plurality of vertically reciprocable needles 10, indicated in cross section in Fig. I. While the illustrative machine is of multiple needle construction certain features of the invention may, if desired, be applied to a single needle machine. A main drive shaft, supported by the standard and extending through the overhanging arm, is provided with a combined pulley and hand wheel through which pow-

er is supplied to the various operating devices in the machine. An oscillatable shaft 11 (Fig. II), supported by suitable bearings 12, is adapted to be operated in properly timed relation to other devices in the machine by appropriate connection with the above-mentioned main drive shaft. An arm 13 secured to the shaft 11 has attached to its upper end a feed dog bar 14 carrying a feed dog 15 (Fig. I). As shown, portions of the feed dog are arranged to pass upwardly through, and longitudinally of, slots 16 formed in a throat plate 17 constituting a part of the work supporting surface of the machine.

Also extending longitudinally of the base portion of the machine and suitably journaled in bearings carried by the latter is a rotatable shaft 18. This may be connected with the main drive shaft, hereinbefore mentioned, through gearing of the type disclosed in said Quist application, or in the patent to Christensen No. 2,113,572, granted April 12, 1938. An eccentric carried by the shaft 18 cooperates with a strap 19 (Fig. II) and serves to impart the desired lifting and lowering movements to the feed dog 15. A pair of spiral gears 20, secured to the shaft 18, meshes with cooperating spiral gears 21 (Fig. III) each of which is secured by a set-screw 22 to a hollow, vertically extending shaft 23 which carries at its upper end the rotary component of a rotary loop-taker or hook designated generally as 24. The two hook units, each including a shaft 23 and its associated hook 24, are substantially identical except for the fact that certain parts of one unit are of right hand construction while those of the other are of left hand construction. It will be sufficient, therefore, for a full understanding of the invention to describe only one of the units in detail.

Gears 20 and 21 are of such relation that the hook shaft 23 will be rotated at twice the angular speed of the shaft 18. Accordingly, two revolutions will be given to the rotary component of the hook for each stitch-forming cycle of the machine. Shaft 23 is journaled in suitable bushings 25 and 26 mounted in spaced portions 27a and 27b of a saddle or frame 27 constituting the main support for the rotary hook and the associated devices. Gear 21 is secured to the shaft 23 between the bushings 25 and 26 within a recess 28 formed between the spaced portions 27a and 27b of the frame. The latter is adjustably carried by the base portion 9 of the machine and for this purpose is provided with a split collar extension 29 (Figs. II and VII) adapted to surround a bushing 30 extending through and projecting laterally from one of a pair of bearing supports 31 for the shaft 18. A clamping screw 32 serves to clamp the split collar in adjusted position on the bearing sleeve. At its opposite end the frame 27 is provided with an extension 33 having a rounded upper surface 34 (Fig. VII) adapted to cooperate with a flat under surface on a portion 35 of the base 9. A screw 36, passing through an elongated slot 37 (Fig. II) in the extension 33, has screw-threaded engagement with the portion 35 of the base and when tightened serves to clamp the corresponding end of the frame 27 in place. It will be seen from the foregoing that the frame 27 may readily be adjusted along the bushing 30 and portion 35 of the base of the machine. Screws 32 and 36 may simply be loosened for this purpose and then tightened again to clamp the frame in the desired position. A screw 38, which serves to secure the spiral gear 20 to the shaft 18, may be manipulated at the same time

5 to maintain the proper relationship between the gears 20 and 21 as the frame is adjusted. Allowance may thus be made for different sized needles, in single and multiple needle machines, and for different needle spacings in multiple needle machines.

As an integral part of the frame 27 there is provided a chamber 39, laterally in line with the hook shaft 23, which constitutes a lubricant reservoir for the oil utilized in lubricating various surfaces of the hook unit. A relatively large opening is provided at one side of the reservoir, this being closed by a plate 40 and a gasket 41 clamped in place by any suitable means such as screws 42. The lubricant may be introduced through a closable cup 43 fitted into a suitable opening at the top of the chamber 39. At its upper end this chamber communicates with another chamber 44 which extends laterally toward the shaft 23 and constitutes an extension of the reservoir space. The lower end of the chamber 39 is connected by a passage 45 with another, smaller chamber 46 formed in an extension 47 (Fig. III) at the bottom of the frame. Chamber 46 constitutes an auxiliary reservoir, at the lower end of the hook shaft 23, which may be considered an extension of the main reservoir. This auxiliary reservoir is closed by means of an adjustable screw threaded plug 48 cooperating with threads in the bottom of the extension 47. When the plug is turned to the desired position, it may be locked in place by a nut 49 which may, at the same time, clamp a gasket 50 against the under surface of the extension 47. In the upper surface 51 of the plug there is provided a diametrical groove or slot 52 adapted to receive a tongue 53 at the lower end of a core pin 53. This core pin is provided with a spiral groove 54 throughout the major portion of its length, commencing at a point a slight distance up from the bottom. Adjacent the two ends of the grooved portion the diameter of the pin is slightly enlarged, as indicated at 55 and 56. These enlarged sections are adapted to fit snugly, i. e. with a bearing fit, within the hollow bore of the shaft 23, while the part of the pin intermediate the sections 55 and 56 is of somewhat reduced diameter. This serves to reduce the friction and to provide, most effectively, the desired oil pumping action to be explained. Above the section 56 the core pin is provided with a tapered or pointed end 57 adapted to cooperate with an aperture in an annular member 58 mounted in the upper end of the shaft 23 or the bottom of the rotating component 59 of the rotary hook.

It will be understood that due to the spiral groove 54 in the core pin, which is held stationary by the screw plug 48, oil that is delivered by gravity from the reservoir into the lower end of the shaft 23 will be elevated by a viscosity pump action created upon the rotation of the shaft 23. The oil so elevated will be forced through the restricted passage between the tapered end 57 of the core pin and the aperture in the member 58 which constitute a needle valve. It will be received by a small pocket above the member 58, formed beneath a plate 60 in the bottom of the rotary component of the hook, and will be delivered from this through a tube 61 to a channel 62 in the wall of the rotary component. This channel forms a raceway for a rib or flange 63 projecting laterally from the wall of a stationary, bobbin carrying component 64 of the hook. It is important that just the right amount of lubricant should be delivered to the raceway 62 to

avoid undue friction and overheating, on the one hand, and to avoid the splattering of oil upon the work or the stitching threads, on the other hand. A very nice and very accurate control of this lubricant supply is provided by the core pin construction and mounting just described. By turning the screw plug 48 the core pin may be lifted or lowered, as desired, to provide just the right restriction between the point 57 and the member 58. This longitudinal adjustment of the core pin, 10 moreover, may be very quickly and simply effected. The screw plug 48 is readily accessible at the bottom of the machine. Accordingly, any variation in the lubrication requirements, due to wear of parts, the use of a lubricant of a different viscosity, or due to a change in the speed of operation of the machine, may be quickly taken care of. Furthermore, the construction is relatively simple and inexpensive to produce. Sufficient freedom of movement is provided between the slot 51 and tongue 52 to make it unnecessary to employ any high degree of accuracy in the production of the parts.

The bushings 25 and 26 may be formed of any suitable material, but they are preferably of a porous, lubricant-absorbing type of material, such as that known as oilite. Ordinarily, the oil level in the reservoir 39 will be such as to create a slight head of oil at the level of the top of the bushing 26. Accordingly, there is a slight tendency toward leakage of oil at this point. To reduce this to a minimum the inner surface of the bushing 26 is provided with a groove 65 of opposite sense to the groove 54 in the core pin. Hence, the groove 65 serves, upon rotation of the shaft 23, to force downwardly into the reservoir 46 any oil which has come between the shaft and the bushing.

Adjacent the upper end of the shaft 23 it is provided with an eccentric portion 66 cooperating with a strap integral with a pitman 67. The latter is apertured adjacent its free end to receive the head of a screw or bolt 68 carried by an arm 69 of a rock member having sleeve portion 70 surrounding a reduced section of a pin 71 carried by the frame 21. A large headed screw 72 is provided to retain the sleeve on the pin. At the upper end of the sleeve a laterally extending arm 73, having an enlarged block-like portion 74 at its free end, serves to support an escapement member 75. This member is secured to the block 74 by a screw 76 and is oscillated upon each revolution of the hook shaft. The operation of the escapement member upon the stationary component of the rotary hook, to enable the thread loop to escape around the retainer which holds the stationary member against rotation, is well known and need not be further described.

The escapement operating mechanism just described is located in the extension 44 of the reservoir. Provision is made for proper lubrication of this mechanism. For this purpose a wick member, such as a felt pad 77, is provided, this extending downwardly from the top of the reservoir to a point near the bottom of the latter. It may suitably occupy substantially the entire passage connecting the reservoir 39 with the extension 44. The upper end of this extension is closed by means of a two-piece cover composed of elements 78 and 79 which are secured by screws or the like to the top of the frame 21. The cover element 78 is provided with an opening 80 surrounded by an upstanding collar 81 adapted to encircle the eccentric 66 and the strap portion of the pitman 67. An

upraised portion 82 of the cover element 78 is adapted to receive and retain a wick or felt pad 83 which at one end engages the top of the wicking 77 and at its other end engages the strap portion of the pitman 67, during a portion of the rotation of the latter. Pad 83 is held up at spaced points by a series of projections 84 on the lower cover element 79 extending inwardly from the sides of an opening 85 aligned with the upraised portion of the top cover element. The lower cover element is also formed with a circular opening 86 aligned with the opening 80.

In the operation of the machine, oil which is elevated by the wicking 77 is delivered to the outer end of the pad 83 and is carried by this to a point adjacent the strap portion of pitman 67. Upon each revolution of the shaft 23 a small amount of this oil is wiped from the pad by the strap and is delivered to a depression 87 in the top of the pitman 67. From this depression a portion of the lubricant is delivered through a small opening 88 to the outer periphery of the eccentric 66 while another portion is delivered to a recess above the top of the bolt 68. The latter oil serves to lubricate the relatively moving surfaces on the connected parts 67, 68 and 69. So also, a part of this oil is delivered along a groove 89 in the upper surface of the arm 69 to an opening 90 through which it is supplied to the bearing surface of the pin 71. Some of the oil delivered to the eccentric 66 may also be carried into the bushing 25 to lubricate the bearing surface of the latter.

While an illustrative embodiment of the invention has been described in considerable detail, it will be understood that numerous changes may be made in the construction, arrangement and cooperation of the various parts without departing from the general principles and scope of the invention. The terms and expressions used herein have been employed as terms of description and not of limitation.

45 What I claim is:

1. In a sewing machine, a vertical axis hook having a hollow shaft connected therewith, said hook having a raceway, a lubricant reservoir communicating with the lower end of said shaft, adjustable means within the bore of said shaft operable only upon rotation of the shaft to induce a flow of lubricant therethrough to said raceway by a positive pumping action dependent upon said rotation, and means so cooperating with said first recited means that adjustment of the latter will vary the quantity of lubricant delivered through said bore to the raceway.

60 2. In a sewing machine, a vertical axis hook having a hollow shaft connected therewith, said hook having a raceway, a lubricant reservoir communicating with the lower end of said shaft, means within the bore of said shaft operable only upon rotation of the shaft to induce a flow of lubricant therethrough to said raceway by a positive pumping action, means adjacent the lower end of said shaft for axially adjusting said means within the bore, and means so cooperating with said first recited means that adjustment of the latter will vary the quantity of lubricant delivered through said bore to the raceway.

70 3. In a sewing machine, a vertical axis hook having a hollow shaft connected therewith, said hook having a raceway, a lubricant reservoir

communicating with the lower end of said shaft, means within the bore of said shaft operable only upon rotation of the shaft to induce a flow of lubricant therethrough to said raceway by a positive pumping action, screw means for adjustably supporting the lower end of said means within the bore of said shaft, and means cooperating with said means within the bore of said shaft for regulating the quantity of lubricant delivered through said bore to the raceway.

4. In a sewing machine a vertical axis hook having rotary and non-rotary components with a raceway therebetween, a reservoir for supplying lubricant to said raceway, an elongated member enclosed in a tubular passage in said rotary component, said member and the wall of said passage being relatively movable and operative upon rotation of said rotary component to induce the flow of lubricant from said reservoir through said passage to said raceway, said member having a tapered end, means cooperating with said tapered end to restrict the flow of said lubricant, and means for shifting said member axially relative to said cooperating means to regulate the flow of lubricant.

5. In a sewing machine a vertical axis hook having rotary and non-rotary components with a raceway therebetween, said rotary component having a pendant hollow shaft, a reservoir for supplying lubricant to said raceway, a member within the bore of said shaft operative upon rotation of said rotary component to positively pump lubricant from said reservoir to said raceway, means cooperating with said member to restrict the flow of said lubricant, and adjustable means for supporting said member and shifting the same relative to said cooperating means to vary the flow of the lubricant.

6. In a sewing machine a vertical axis hook having rotary and non-rotary components with a raceway therebetween, said rotary component having a pendant hollow shaft, a reservoir for supplying lubricant to said raceway, a member within the bore of said shaft operative upon rotation of said rotary component to induce the flow of lubricant from said reservoir to said raceway, said member having a tapered end, means cooperating with said tapered end and forming a needle valve therewith to restrict the flow of said lubricant, and adjustable means for supporting said member and shifting the same relative to said cooperating means to vary the flow of the lubricant.

7. In a sewing machine a vertical axis hook having rotary and non-rotary components with a raceway therebetween, said rotary component having a pendant hollow shaft, a reservoir for supplying lubricant to said raceway, a member within the bore of said shaft operative upon rotation of said rotary component to induce the flow of lubricant from said reservoir to said raceway, said member having a tapered end, means cooperating with said tapered end and forming a needle valve therewith to restrict the flow of said lubricant, and an adjustable screw plug axially aligned with said member and arranged to support the same.

8. A vertical axis hook unit which comprises a frame, a hollow shaft journalled in said frame, a rotary hook component carried by said shaft, a stationary hook component cooperating with a raceway in said rotary component, a chamber in said frame providing a lubricant reservoir, the bore of said shaft communicating with

said reservoir, a member within said bore adapted to positively pump lubricant from said reservoir to said raceway upon rotation of said rotary component, means for shifting said member axially within said bore, and means cooperating with said member to regulate the flow of lubricant by axial shifting of said member.

9. A vertical axis hook unit which comprises a frame, a hollow shaft journalled in said frame, a rotary hook component carried by said shaft, a stationary hook component cooperating with a raceway in said rotary component, a chamber in said frame providing a lubricant reservoir, the bore of said shaft communicating with said reservoir, a member within said bore adapted to induce the flow of lubricant from said reservoir to said raceway upon rotation of said rotary component, means cooperating with said member to limit the flow of lubricant, and means for holding said member stationary during rotation of said component, said last named means being adjustable to shift said member relative to said cooperating means and thereby vary the flow of lubricant.

10. A vertical axis hook unit which comprises a frame, a hollow shaft journalled in said frame, a rotary hook component carried by said shaft, a stationary hook component cooperating with a raceway in said rotary component, a chamber in said frame providing a lubricant reservoir, the bore of said shaft communicating with said reservoir, a member within said bore adapted to induce the flow of lubricant from said reservoir to said raceway upon rotation of said rotary component, means cooperating with said member to limit the flow of lubricant, and an adjustable screw plug in the bottom of said frame for supporting said member in variable relation to said cooperating means and holding said member against rotation.

11. A vertical axis hook unit which comprises a frame, a hollow shaft journalled in said frame, a rotary hook component carried by said shaft, a stationary hook component cooperating with a raceway in said rotary component, an escapement member cooperating with said stationary component, connections from said shaft for actuating said escapement member, a chamber in said frame providing a lubricant reservoir, the bore of said shaft communicating with said reservoir, a member within said bore adapted to induce the flow of lubricant from said reservoir to said raceway upon rotation of said rotary component, means for shifting said member axially within said bore to regulate the flow of lubricant, and wick means within said frame effective upon rotation of said rotary component to deliver lubricant from said reservoir to said connections.

12. A vertical axis hook unit which comprises a frame, a shaft disposed vertically in said frame, a rotary hook component carried by said shaft, a stationary component having bearing surfaces cooperating with said rotary component, a chamber in said frame forming a lubricant reservoir, means for delivering lubricant from said reservoir to said bearing surfaces upon rotation of said shaft, an escapement member cooperating with said stationary component, driving means connected with said shaft above the level of the lubricant in said reservoir for actuating said escapement member, and wick means in said frame extending from said reservoir to a

9

point adjacent said driving means effective upon rotation of said rotary component to deliver lubricant from said reservoir to said driving means.

13. A vertical axis hook unit which comprises a frame, a shaft disposed vertically in said frame, a rotary hook component carried by said shaft, a stationary component having bearing surfaces cooperating with said rotary component, a chamber in said frame forming a lubricant reservoir, means for delivering lubricant from said reservoir to said bearing surfaces upon rotation of said

5

shaft, an escapement member cooperating with said stationary component, means connected with said shaft for actuating said escapement member, a removable cover over said actuating means, a wick element carried by said cover, means for delivering lubricant from said reservoir to said wick element, and means effective upon rotation of said rotary component for removing lubricant from said wick element and delivering it to said actuating means.

10

GEORGE SAUER.
